5 Claims. (Cl. 62—1)

1

This application is directed to a process and apparatus for converting hydrocarbons in the presence of a particle-form solid contact mass. It has particular relation to a method and apparatus for adjusting the temperature of hot granular contact material in continuous moving bed conversion systems.

Various hydrocarbon conversion processes are known in which a hydrocarbon liquid or vapor is brought into contact with a comminuted solid material at a suitable, high temperature and for a sufficient period of time to provide a substantial conversion of the hydrocarbons into other more desirable hydrocarbons. In these conversion processes a carbonaceous deposit is formed on the solid contact material impairing the function of the contact material, making it essential that the deposit be removed therefrom. It is customary in these processes to regenerate or restore the contact material to its former condition by burning the carbonaceous deposit from the contact material.

In a preferred form of hydrocarbon conversion the solid contact material is continuously passed through a conversion zone as a substantially compact moving column of particle-form material. Hydrocarbons are admitted to the conversion zone and converted products removed therefrom continuously for long periods of time. The particle-form material is continuously withdrawn from the zone, contaminated with carbonaceous material. The contaminated material is then passed downwardly as a substantially compact column through a burning zone wherein the carbonaceous material is burned from the contact material, restoring the contact material substantially to its original state.

The burning of carbonaceous material on the solid contact material is highly exothermic. In many instances it is necessary to extract heat from the contact material before it can be transported through elevators which would be damaged by the excessive temperature of the material or before it can be supplied to the reaction vessel for further hydrocarbon conversion. The nature of the problems involved and the manner in which they are met by the present invention is well illustrated by apparatus for conversion of higher boiling hydrocarbons to ethylene by reaction for a very short time, say 0.2 second at high temperatures on the order of 1500° F. and above. To obtain the necessary short reaction time the high temperature reaction mixture must be promptly quenched to a low temperature. One advantageous system for accomplishing this high tem-

perature short time reaction is to pass the charge hydrocarbons in direct contact with a bed of highly heated granular solid and then pass the hot reaction mixture through a bed of relatively cold granular solid. This requires two contacting chambers connected by a transfer line which will confine the hot gaseous mixture within a predetermined path. The hot contact material from the reaction chamber on which carbonaceous material is deposited during the conversion reaction is cooled from about 1000 to 1100° F. down to about 500 to 800° F., lifted by a suitable elevator to a heater, in which the carbonaceous material is burned from the material, and then readmitted to the reaction chamber as a downwardly moving column of contact material.

This problem is also illustrated by the adiabatic TCC process, in which solid contact material is passed downwardly as a substantially solid column through a reaction zone wherein it is contacted with hydrocarbons which are converted to suitable hydrocarbons in the gasoline range in substantial amounts and the contact material is then passed downwardly as a substantially solid column through a regeneration zone in which the contact material is contacted with a combustion supporting gas to burn off the carbonaceous deposits on the surface of the material. In the prior TCC processes, the regeneration, generally, provided sufficient heat to damage the catalyst, requiring the removal of heat from the kiln. This was accomplished by dividing the kiln into a series of burning and cooling zones. The temperature of the catalyst leaving each burning zone was controlled partly by the number of cooling coils in service in the following cooling zone. The cooling in the cooling zone was provided, generally, by one or more levels of horizontal, spaced tubes. Water was circulated through the number of tubes necessary to give the required cooling. Thus the effective heat transfer surface was varied by the number of tubes through which cooling water was circulated. In normal cracking operations, the reactor conditions vary frequently, which, in turn, causes variations in the amount of heat generated in the kiln and, therefore, the amount of heat which must be removed in the cooling zones. This requires cutting water flow in and out of some of the tubes. Since a tube which does not have water flowing through it may be at a temperature of about 1100° F., for example, while the water used for cooling may be only 200 to 400° F., severe stresses are set up in the tubes each time water is cut in or out. This caused frequent failure of

the tubes, particularly at the location where they are sealed into the header.

In the recent adiabatic process the catalyst flow rate is increased substantially, approximately 2 or 3 times the old rate. Consequently, the carbon lay down on the catalyst during reaction is reduced because the catalyst is retained in the reactor a shorter period. The temperature reached in the regenerator, therefore, is maintained below the heat damaging level because there is a smaller per cent of carbon to be burned therein. The catalyst enters the kiln at approximately 850° F. and is withdrawn at approximately 1200° F., below the heat damaging temperature limit. No heat transfer tubes are needed in the kiln, permitting the kiln design to be exceedingly simple and easy to service. But, as previously indicated, generally, more heat is released in the kiln than is needed in the reactor, and, therefore, there is presented the problem of removing this excess heat from the system. A catalyst cooler of some sort must be included in the system, usually located subsequent to the kiln.

Prior art catalyst or pebble coolers are not found satisfactory for a variety of reasons. Inasmuch as more or less heat must be extracted from the catalyst from time to time, some means of control of the cooler characteristics is required. For example, many coolers allow the coolant to flow through exchanger tubes, being equipped with controls for preventing the flow of coolant through selected tubes. The empty tubes assume the temperature of the moving contact material. Consequently, when they are put back in service, the cold coolant fluid contacts the hot walls of the tube, causing the metal to spall and crack. This necessitates frequent cooler repair and replacement. Many of the prior coolers are disfavored because of their complexity, excessive cost or difficulty of control. Because of their tendency to develop leaks, the use of cooling fluids under pressure was largely precluded in the prior art coolers.

Moving bed catalyst systems of hydrocarbon conversion are effectively replacing fixed bed systems of operation. They have proved to be economical in the larger units of a size about 10,000 to 15,000 barrels per day. Usually, the kiln is divided into a series of stages with burning stages followed by cooling stages. Generally the cooling stage comprises one or more bundles of horizontal cooling pipes. In attempting to produce a smaller unit, handling about 2,000 to 3,000 barrels a day of charging stock, the cost of the kiln was found not to reduce in proportion to reduction in cost of the remaining equipment. By making the kiln without tubes, and providing a simple cooler adapted for use outside of the kiln, the unit has been found to provide an economically feasible moving bed system for the small refiner.

It is not intended that this invention be limited to the specific embodiments shown. One of the broader aspects of this showing involves using a catalyst or pebble cooler in which is located a heat exchanger, adapted to place particle-form contact material in indirect heat exchange relationship with a cooling fluid. The heat exchanger is maintained flooded with coolant fluid throughout the entire contact surface area. Molten salts such as potassium nitrate or nitrite may be used as the coolant fluid, as well as molten metals but liquid water, maintained under pressure, is preferred. For example, water pressures of 300-350 pounds per square inch may

be used, with the temperature being maintained constant at the boiling temperature by maintaining the water pressure at a fixed value. The temperature of the contact material is controlled by varying the volume of the contact material brought into contact with the cooling surface.

The object of this invention is to provide a simple method of cooling and adjusting the temperature of hot granular contact material.

A further object of this invention is to provide a simple cooler for cooling and adjusting the temperature of hot, particle-form contact material.

Another object of this invention is to provide an improved hydrocarbon conversion process.

Another object of this invention is to provide an improved process for the catalytic cracking of hydrocarbons.

These and other objects of this invention will be made apparent in the following discussion of the invention, read in conjunction with the attached sketches. The sketches are intended to illustrate the invention, and are highly diagrammatic in form.

Figure 1 is a diagrammatic showing of the relationship of the several elements making up a plant for the conversion of hydrocarbons to ethylene.

Figure 2 is a detail view in section of the reactor outlet port of Figure 1 and the cooler located therebelow.

Figure 3 is a plant for conducting hydrocarbon conversion in accordance with adiabatic TCC principles.

Figure 4 is a view, partially in section, of the cooler used in the plant of Figure 3.

Figure 5 is a vertical section showing a variant form of cooler design.

Figure 6 is a vertical section showing a further embodiment of the invention.

Figure 7 is a plan view of the iris valve shown on plane 7-7 of Figure 6.

Referring specifically now to Figure 1, a hot granular solid is heated to a suitable high temperature in heater 10 and transferred by feed leg 11 through a steam sealing zone 12 to a reactor 13. A charge for the reaction is introduced by a plurality of inlet tubes 14 depending from ring manifolds 15 at the top of the reactor. Within the reactor 13 the charge is passed in direct contact with the highly heated granular solids and is thus rapidly converted to a vapor phase mixture having the temperature desired for the reaction. Upon leaving the contact bed, the reaction mixture is quenched by the injection of water supplied from inlet 16 and is passed by conduit 17 to a quencher 18 wherein it is passed through a moving bed of relatively cool granular solids for further reduction in temperature. The quenched reaction mixture is transferred by line 19 to a spray condenser 20 from which product vapors are taken overhead by line 21 to a suitable gas plant for purification and recovery of the gaseous products of the reaction. Oil and water from the bottom of condenser 20 are passed to a settler 22 wherein they separate into an upper oil layer which is cooled in heat exchanger 23 before transfer to processing or storage and a lower water layer which is cooled in heat exchanger 24 to be recycled in part to the spray condenser by line 25. If the charge to the reactor is in liquid phase, water from the bottom of settler 22 may be used in the charge, since contamination of the charge water has no detrimental effect in such operations, the contaminants

being either vaporized with the water or deposited on the granular solid from which they may be removed by burning in the heater.

Returning now to the reactor 13, a purge gas such as steam is admitted to the bottom of the reactor at inlet 26 and a pressuring medium, which may also be steam, is admitted at inlet 27 to be used to provide a pressure seal in the insulation of the vessel for preventing deposition of carbonaceous substances in the reactor insulation. The granular solids are withdrawn from the bottom of reactor 13 by pipe 28 and are passed through a cooler 29 and depressuring pot 30 and then to the bottom of the elevator 31. In general, solids transferred to the elevator must be maintained at a temperature which will not damage the elevator or adversely affect its operation. The excess heat is extracted from the solids in the cooler 29. Solids are discharged from the top of elevator 30 into a feed pipe 32, passed through a classifier 33 for removal of particles broken down to a size smaller than that desired and are then fed to heater 10 to again pass through the cycle. In the heater, fuel from inlet 34 is burned in preheated air supplied at 35 to generate a flame in direct contact with the solid granules and thus heat the latter to the desired degree. Flue gases are withdrawn at 36 and passed to an economizer or stack.

The quencher is an element of a similar cycle of granular solids and wherein the granules serve to cool vaporous reaction mixture from reactor 13 and are then purged by steam admitted at 37 and passed by pipe 38 through the cooler 39 and depressuring pot 40 to an elevator 41. From the top of the elevator 41 the solids are discharged by pipe 42 through a classifier 43 to a hopper 44. Solids are supplied through feed leg 45 to an air preheater 46 wherein they are contacted with air from blower 47 to preheat the same. The preheated air is then transferred by line 48 to inlet 35 of heater 10. Any carbonaceous deposit in the nature of coke or tar laid down on the solids in the quencher 18 will be burned off in heater 46 but a large excess of air is supplied to chamber 46 and the net effect is to cool the solids in chamber 46 whereupon the cold granules are transferred by feed leg 49 through a steam purging zone 50 to the quencher 18. Details of the internal structure of these vessels may be found in copending application Serial No. 670,277, now United States Patent No. 2,520,482 which issued on October 29, 1950.

Referring now to Figure 2, the internal structure of the coolers 29 and 39 is shown. The outlet of the reactor projects through the top of the cooler 29. Within the cooler the outlet conduit of the reactor is surrounded by an axially aligned conduit 51 which is adapted to be raised or lowered with respect to the outlet conduit. The exterior portion of the conduit possesses a rack gear 52 adapted to mate with the pinion gear 53 providing a telescoping motion for the aligned conduits. The pinion gear is driven by a suitable prime mover, such as an electric motor, not shown. In the lower portion of the cooler is located the upper and lower tube sheets 54, 55 between which is fastened vertical connecting tubes 56, adapted to pass particle-form material through the exchanger section. The flow of contact material from the transfer tubes is controlled by the valve 8 in the outlet conduit located therebelow. A cooling solution is circulated around the vertical conduits, heat being extracted by flow of the cooling fluid according to

the thermo-syphon principle. Gaseous coolant is withdrawn from the heat exchanger section through the conduit 57 to the tank 58 located above the exchanger section. Within the tank 58 the gaseous coolant condenses back to a liquid. Coolant liquid is continuously withdrawn from the bottom of the tank to the heat exchanger section of the cooler through the conduit 59. A cooling fluid is passed through a continuous conduit in the vessel 58 to extract the heat therefrom. The cooling fluid is introduced through the conduit 60 from a source not shown and removed through the conduit 61.

By the above procedure, the heat exchanger section of the cooler is maintained flooded with constant temperature coolant liquid at all times.

The amount of heat to be extracted from the granular material varies with a number of factors such as, for example, the amount and type of reactants fed to the bed of granular material in the reactor 13. It is obviously desirable to extract only sufficient heat from the granular material to prevent damaging the elevator and its related parts from the excessive temperature of the contact material. By rotating the pinion gear 53 the sliding conduit 51 may be raised or lowered to cause the pile 60 to spread out over a larger or smaller area of the tube sheet 54. The pile will only flow until the angle of repose of the contact material is reached, making the area of the tube sheet covered dependent upon the height of the bottom of the conduit 51 above the upper tube sheet 54. As less area of the tube sheet is covered, fewer of the vertical tubes 56 will be used for transferring the granular material through the heat exchanger. Inasmuch as the temperature of the coolant fluid is maintained constant by the thermo-syphon principle of operation, less heat will be extracted from the granular material when fewer tubes are used for the transfer of the contact material because less volume of the contact material is brought into contact with the cooling surface.

It is seen that a ready means of adjusting the temperature of the contact material, while maintaining a flooded heat exchanger with coolant liquid at a substantially fixed temperature, is provided.

Referring now to Figure 3, a system is shown for carrying out adiabatic regeneration in a TCC process. A downwardly moving column of catalyst particles in the reactor 70 is contacted with the hydrocarbon charge admitted through the conduit 71 from a stock preparation zone, not shown. The products produced by the catalytic conversion of the hydrocarbon charge are removed through the conduit 72 to other apparatus, not shown, for further treatment. The fouled contact material is removed from the bottom of the reactor 70 through the conduit 73 to the regenerator 74. The flow of contact material in the conduit 73 is controlled by the valve 75. Air is admitted to the regenerator 74 through the conduit 76 to burn off the carbonaceous material from the surface of the contact material moving through the vessel as a descending substantially solid column. The flue gas formed in the regenerator is removed through the conduit 77. In this process the catalyst flow rate is sufficiently rapid to prevent the contact material being overheated in the regenerator. For example, the material enters the regenerator at a temperature of about 850° F. and is removed therefrom at a temperature of about 1200° F. In this system no heat exchanger tubes are required in the regenerator.

making the regenerator construction simple. In addition, the regeneration gas flow may be limited to a value slightly in excess of that required for complete combustion of the coke. For example, the flow of air to the regenerator may be limited to a rate of flow which is about 20 per cent in excess of that required for chemically correct combustion of the coke deposits present on the catalyst.

The contact material removed from the regenerator 70 is passed through the conduit 78 into a cooler 80 disclosed in more detail on Figure 4. The cooled catalyst is discharged from the cooler 80, is passed through the conduit 81 and lifted by the gas lift 82. The valve 83 in the conduit 81 is used to control the discharge of catalyst from the cooler. Lift gas is introduced near the bottom of the lift through the conduit 84 and the catalyst is lifted by the lift gas and raised to the top of the lift. The lift gas may be inert gas, steam, flue gas or air. The catalyst is separated from the gas in the disengaging chamber 85, and delivered through the conduit 86 to the hopper 87. The lift gas is discharged from the disengaging chamber through the conduit 88. During regeneration of the catalyst water is removed from association with the catalytic material. When the dehydrated catalyst is again contacted with steam, the catalyst rapidly adsorbs the steam with the release of great quantities of heat described as heat of hydration. For some catalytic materials this may involve a heat release equal to or greater than the heat of hydrocarbon conversion, however, certain of the synthetic catalysts have heats of hydration which are much lower. Hydration of the catalyst is performed in the hopper 87 by introducing steam through the conduit 90 at a rate controlled by the valve 91. The conduit is connected with a multiplicity of perforated pipes in the base of the hopper which provides for uniform distribution of the steam throughout the gravitating mass. The excess steam may be removed through a vent in the roof of the hopper. The catalyst flows from the hopper 87 through the connecting feed leg 89 into the reactor 70, thereby completing the continuous catalyst flow path. Various seals are used to prevent the transfer of gases from one vessel to another; inert gases are used to purge catalyst moved from one vessel to another. These details are not shown on the Figure 3, but can readily be found in the various patents on moving bed catalytic cracking.

Due to increased demand for gasoline and the increased amount of crude stocks converted to gasoline to meet this demand, it is now necessary that heavier stocks, for example, stocks which are normally liquid at reactor feed temperature, be charged to the reactor. Because these heavier stocks are more sensitive to thermal conditions, and thermally crack at or about reaction temperatures, they are charged at lower temperatures in liquid form. For example, the liquid and vapor feed can be charged to the reactor at about 700° F. Suitable reaction temperatures run about 850° F. to about 950° F., depending upon type of catalyst, reaction conditions, type of feed stock, etc. A system for feeding mixtures of liquid and vaporous hydrocarbons to a reaction vessel is shown in copending case Serial Number 719,724 filed January 2, 1947, now United States Patent No. 2,574,850 which issued on November 13, 1951. Sufficient heat is extracted from the catalyst withdrawn from the regenerator in the cooler to leave enough sensible heat and potential hydra-

tion heat in the catalyst to supply the total heat required in the reactor. This may be only reaction heat or it may be reaction heat plus sensible and latent heat to get the reactants into vapor phase at the desired reaction temperature. The reactor can be operated with concurrent or countercurrent flow of reactants and catalyst mass, and the reactants may be charged in liquid form, vapor form, or a mixture of both liquid and vapor.

It is possible to remove some heat from the kiln, when found expedient, by recirculating cooled flue gas or by using heat transfer tubes in the regenerator, but it is preferred to cool in the cooler as indicated herein.

The continuous system may be operated at a catalyst to oil ratio of about 1-20 pounds of catalyst per pound of oil, and at space velocities of about 0.5-10 volumes of oil (measured at 60° F.) per hour per volume of contact material column within the conversion zone. The conditions will vary somewhat with catalyst material, catalyst activity, type of feed stock, etc. In such processes it is found desirable to limit the particle size broadly within the range of about 3 to 100 mesh and preferably within the range of about 4 to 20 mesh Tyler Standard Screen analysis. The percentage of fines present in the contact material mass should be maintained as low as possible.

Referring now to Figure 4, an enlarged view of the cooler 80 of Figure 3 is shown, partially in section. The catalyst introduced into the cooler 80 forms a pile below the conduit 78. The short conduit 79 below the conduit 78 is somewhat larger in cross-section than the conduit 78 and is adapted to be raised or lowered by the lever 65 pivoted in the bearing 66. The conduit 79 is operated by the wheel 67 which operates the mating gears 68, 69. The shaft 64 maintains the conduit 79 in substantial alignment with the conduit 78. A series of cooling conduits or tube bundle 90 is located in the cooler 80, with or without deflecting baffles. The bundle is arranged to provide paths for the catalyst which bring the catalyst in contact with the cooling surface during its downward travel. The cooled catalyst is discharged from the bottom of the cooler through the conduit 81, the flow being controlled by the valve 83. The tube bundle 90 is supplied with a suitable coolant from a source, not shown, through the conduit 91 and the coolant is discharged through the conduit 92.

Referring now to Figure 5 another embodiment of the invention is shown. Downwardly moving contact material is introduced through the conduit 95 into the top of the cooler 96. The contact material is received in the enclosed chamber 96 and discharged from the bottom of the chamber 96 through a multiplicity of conduits 97 adapted to distribute the contact material evenly across the cross-sectional area of the cooler. Valves 98 are located in the conduits 97 for controlling the flow of contact material through the conduits. By closing the valves in the outer conduits the pile of contact material below the valves may be made to cover a smaller area of the cross-section of the cooler. In the lower section of the cooler are located upper and lower tube sheets 99, 100 and a multiplicity of transfer tubes 101. Thus more or less of the transfer tubes 101 may be filled with contact material by the control of the valves 98. The space surrounding the tubes 101 is filled with a cooling fluid supplied through the conduit 102, and discharged through the conduit 103. The

temperature of the coolant may be maintained substantially constant by suitable control of the valves 104, 105 located in the conduits 102, 103. This may suitably be done by a controller 106 connected to a temperature indicator 107, and adapted to automatically control the valves 104, 105. The cooled contact material is discharged from the cooler 96 through the conduit 108. As indicated the valves 98 may be controlled by a central controller 109 adapted to maintain a substantially constant temperature in the outlet conduit 108.

In Figure 6 is shown still another embodiment of this invention. In the top of the cooler 110 is projected the conduit 111 adapted to introduce contact material onto the shelf or floor 112. The shelf or floor 112 has an orifice in its center adapted to pass contact material therethrough onto the top of an iris diaphragm 113. In the lower section of the cooler 110 are located tube sheets and transfer tubes, similar to those previously described, adapted to permit the transfer of contact material downwardly through the tubes in contact with a cooling fluid. By the indicated system of gearing the iris diaphragm may be opened or closed to cause the pile of contact material on the upper tube sheet to cover a large or smaller area of the tube sheet, thereby controlling the number of transfer tubes through which the contact material is passed. The iris diaphragm 113 is driven by the motor 114 through the speed reducer 115. The motor 114 can be controlled by a controller 116 adapted to maintain the temperature of the contact material in the outlet conduit 117 substantially constant. The iris diaphragm serves only as a baffle and is not a throttling device. The diaphragm completely closed will permit the transfer of sufficient contact material to meet the needs of the system.

Figure 7 shows a plan view of the iris diaphragm of Figure 6 as seen on plane 7-7 of Figure 6. The leaves 118 of the diaphragm are attached by the members 119 to a suitable support frame, which, in turn, is supported by the cross supports 120, attached to the inner wall of the cooler. The ring 121 is fastened to a second frame by the cap screws 122 and the leaves are fastened to this frame by the cap screws 123. The quadrant of a gear 124 is attached to the ring 121 by the bar 125. Rotation of the gear 124, effected by rotation of a mating pinion gear not shown, causes the ring 121 to rotate and thereby causes the leaves 118 to pivot on the pivot points 119. The rotation of the leaves 118 causes the central opening to increase or decrease, depending upon the direction of rotation of the leaves 118.

This application shows broadly a method and apparatus for cooling granular contact material which is related, in some of its broader aspects, to the copending application Serial Number 154,130, filed April 15, 1950.

What is claimed is:

1. A cooler for comminuted solid contact material comprising an enclosed vessel, a downwardly directed feeding conduit projected into the top of said vessel and terminating near the top thereof, a short conduit telescoping the end of said conduit adapted for movement in an axial direction, said short conduit having an axially aligned rack gear located on its outer surface, a pinion gear disposed adjacent said short conduit and adapted to engage and drive said rack gear, means for driving said pinion

gear, cooling means defining a multiplicity of downwardly directed paths disposed in the lower section of said vessel through which contact material may be lowered as substantially compact columns, means for introducing coolant fluid into the cooling means, means for withdrawing coolant fluid from the cooling means, said cooling means adapted to bring the coolant fluid into indirect heat exchange relationship with the contact material throughout the entire length of the paths, and means defining an outlet in said vessel through which cooled contact material may be withdrawn.

2. In a cooler for granular contact material in which a heat exchanger is located in the bottom portion thereof arranged to provide a multiplicity of downwardly directed paths substantially equally distributed across the cross-section of the cooler, the method of operation which comprises: the steps of maintaining the heat exchanger flooded with cooling fluid, introducing the contact material into the cooler at a location near the top thereof, gravitating the contact material through a depending conduit terminated at a location above the heat exchanger, discharging the contact material from the conduit to form a pile on top of the heat exchanger, gravitating the contact material through the heat exchanger paths located directly below the pile of contact material, adjusting the elevation of the outlet of the depending conduit to cause the pile of contact material to cover a sufficient portion of the area of the top of the heat exchanger, so that enough paths are filled with contact material to extract from the contact material the desired amount of heat and withdrawing the cooled contact material from the bottom of the cooler.

3. The method of changing the temperature of a particle-form solid contact material which comprises: passing the contact material through a confined heat exchange zone to contact a heat transfer surface along at least a portion of one side thereof, subjecting substantially the entire area of the opposite side of said heat transfer surface to the influence of a fluid heat exchange medium existing at a temperature substantially different from that of said contact material and maintained out of communication with the contact material, discharging the contact material from said heat exchange zone and selectively controlling the temperature of the contact material discharged at the desired level by adjustably controlling the volume of contact material within said zone which is at any instant under the influence of said heat transfer surface.

4. A cooler for comminuted solid contact material comprising an enclosed vessel, cooling means defining a multiplicity of downwardly extending paths disposed in the lower section of said vessel through which contact material may be lowered as substantially compact columns, means for introducing cooling fluid into the cooling means, means for withdrawing cooling fluid from the cooling means, said cooling means adapted to bring the cooling fluid into indirect heat exchange relationship with the contact material throughout the entire length of the paths, means defining an inlet in the upper portion of the vessel for the introduction of contact material, baffling means operatively connected to said inlet means for controlling the area of the top of said cooling means covered by said contact material, means for adjusting the baffling means,

whereby the required number of paths are filled with contact material to effect the desired temperature adjustment and means defining an outlet in said vessel through which cooled contact material may be withdrawn.

5. A cooler for comminuted solid contact material adapted for gravitation therethrough of a compact column of hot contact material comprising: an enclosed vessel, cooling means defining at least one downwardly extending path for flow of solid contact material within said vessel, means for introducing coolant fluid into the cooling means, means for withdrawing coolant fluid from the cooling means, said cooling means adapted to provide a predetermined surface area for contact with the column of contact material which is in flooded contact with cooling fluid at all times and which places the contact material in indirect heat exchange relationship with the cooling fluid, means defining an inlet for the introduction of contact material into the upper portion of the vessel, baffling means operatively connected with said inlet, adapted to direct the column of the contact material into contact with at least a portion of the cooling means, means for adjusting the baffling means, to vary the amount of cooling surface contacted with contact material and means defining an outlet

in the bottom of said vessel through which the contact column may be withdrawn.
